CONCRETE FORM

Le Roy W. Westcott, Hartford, Mich.

Application July 8, 1937, Serial No. 152,651

2 Claims. (Cl. 25—121)

It is aimed to provide a novel apparatus whereby the walls, blocks or sections may be expeditiously made and such an apparatus or form as is readily disassembled, and further to provide for reinforcement at the junction of blocks as by pilasters, poured concrete and the like.

It is further aimed to provide such a wall or block as may have its surface ornamented or figured, colored or otherwise as preferred.

10 The more specific objects and advantages will become apparent from a consideration of the description following taken in connection with the accompanying drawing illustrating an operative embodiment.

15 In said drawing:—

Figure 1 is a view of the apparatus in side elevation, resting on a table or support;

Figure 2 is a top or plan view of the parts of Figure 1;

20 Figure 3 is a detail section taken on the line 3—3 of Figure 2;

Figure 4 is a detail perspective view of one of the skeleton forms employed;

25 Figure 5 is a detail perspective view of a pair of core sections; and

Figure 6 is a detail perspective view fragmentarily showing a wall constructed by precast blocks according to the invention.

Referring specifically to the drawing wherein like reference characters designate like or similar parts, the invention is practiced by using two metallic skeleton frames 10 of the shape shown in Figure 4, such frames having openings 11 therethrough, short longitudinal extensions 12 at one end and a longitudinal extension 13 at the other end longer than those at 12. As shown in Figures 1, 2 and 3, the frames 10 are adapted to be arranged in parallelism supported on a table 14 or otherwise and core sections 15, one for each opening 11 is adapted to be passed through the opening 11 removably. Said core sections comprise U-shape members 16 and 17, preferably of metal, which are adapted to fill the openings 11 and be held in intimate contact with the walls thereof by means of removable wedges or pillars 18, of wood, metal or any other preferred material.

Reinforcing wires or rods of metal as at 19 are adapted to be arranged against opposite surfaces 50 of the cores held in place as by means of the wires engaging adjacent structure. Thereafter, with the aid of panels, forms or the like, concrete or similar material is adapted to be poured between frames 10 and around the form made up 55 in Figures 1, 2 and 3 and with the aid of a trowel,

form blocks or sections like those shown at 20 in Figure 6. After the concrete or material of the blocks 20 has sufficiently set or hardened, the wedges 18 may be removed whereupon the members 16 and 17 will collapse and may be readily removed from the openings 11, following which, the skeleton frames 10 are disassembled, and the block removed from the table or support 14.

It will be noted that the blocks 20 have spaces 21 therein provided by the cores 15 and at one end have a long flange 13', formed after the extension 13 and at the other end have short parallel flanges 12' formed after the extensions 12.

The blocks 20 may be arranged in wall or other formation as in Figure 6. Where the flanges 13' 15 abut end to end, they may be reinforced by engaging pilasters 22, being cemented thereto and to each other and where the flanges 13' engage at right angles as shown at the corner in Figure 6, concrete or the like may be poured into the space 20 23 to bond the blocks together. Also, concrete may be poured into the space between flanges 12' where they abut end to end, to bond them together.

Attention is called to the fact that the blocks 25 may be made of concrete or other cementitious material of any color or shade and finished of any color or shade and that in addition, the face thereof may be ornamented or figured as preferred. For example, it may be finished to represent a plurality of rows of bricks and in order to provide the necessary grooves, strips such as 24 30 may be placed on the support or table 14. If any other desired configuration is to be imparted to the block, the table 14 may be ornamented or finished accordingly or may even have 35 a die or form supported thereon for contact or engagement by the concrete.

Various changes may be resorted to provided 40 they fall within the spirit and scope of the invention.

I claim as my invention:

1. Apparatus of the class described comprising a plurality of individual skeleton frames, each frame having an opening, an expandible core 45 member separably connecting the frames and disposed in said opening, said core member having a plurality of U-shaped parts having side walls in overlapping relation, and wedge members entering the core members functioning dual- 50 ly to tighten the said parts against the frame and urge the overlapping portions of the side walls into contact.

2. Apparatus of the class described comprising individual skeleton frames, each frame hav- 55

ing a plurality of openings therethrough, removable expandible core members constituting the sole connecting means for the frames bridging the frames and engaging the walls of said openings, said core members comprising a plurality of U-shape parts having their side walls in over-

lapping relation, and wedge members disposable between said parts functioning dually to tighten the said parts against the frame and urge the overlapping portions of the said walls into contact.

LE ROY W. WESTCOTT.
